UNITED STATES PATENT OFFICE.

LAWRENCE W. MAMMEN, OF CHICAGO, ILLINOIS.

AIRSHIP.

Application filed July 10, 1926. Serial No. 121,528.

My invention relates to improvements in a dirigible air ship and more particularly to the type of air ship disclosed in my pending application Serial No. 52,553.

5 My present invention relates to an air ship of a construction formed to assist the lifting medium or gas; wherein the roof or covering of the deck portion is adapted to act as a plane; with the roof of the deck 10 provided with a vacuum forming portion and other refinements in construction over those disclosed in the application referred to being involved, as will be more specifically pointed out in the following detailed 15 description of the accompanying drawings wherein—

Figure 1 is a perspective view of my improved air ship with a portion of the outer covering broken away, to disclose internal 20 construction.

Figure 2 is a horizontal sectional plan of the upper part of the ship, namely the portion located immediately beneath the gas chambers.

25 Figure 3 is a vertical sectional view taken approximately along the longitudinal center-line of the ship.

Figure 4 is a detail sectional view taken on the line 4—4 of Figure 8.

30 Figure 5 is a detail sectional view in perspective of a portion of the keel and a portion of the transverse frame members.

Figure 6 is a detail sectional view showing 35 a portion of the keel and a rib, illustrating the manner of securing same together.

Figure 7 is a schematic elevation of the main portion of the air ship beneath the gas tanks or receptacles with the upper portion omitted illustrating the structure as a 40 heavier than air flying ship.

Figure 8 is a vertical sectional view taken approximately on the offset line 8—8 of Figure 3 looking in the direction of the arrows.

45 Figure 9 is a horizontal sectional view taken substantially on the line 9—9 of Figure 3 looking downwardly.

Figure 10 is a similar view taken substantially on the line 10—10 of Figure 3 50 looking downwardly.

Figure 11 is a perspective view of a portion of the skeleton or frame of the air ship illustrating one end, for example the for-

ward end of the ship; parts of the frame members being broken away.

55 Figure 12 is a detail perspective view of a frame coupler and reenforcing element.

Figure 13 is a schematic view of the body of the ship in vertical section beneath the gas chambers illustrating a part of the frame 60 construction.

Figure 14 is a horizontal sectional view, similar to Figure 9, illustrating a modified form.

65 My invention, as disclosed in the accompanying drawings, relates to improvements in air ships and more particularly to the type of air ship disclosed in my pending application Serial No. 52,553. That is to say, my invention relates to air ships wherein 70 all portions of the air ship proper will be supported from the keel of the ship and the deck-supporting elements so that all strains will be transmitted to the keel; with all of the main frame members formed of comparatively light metal of cross sectional configuration adapted to withstand the strains and stresses; the main frame members of my improved ship being preferably T-shape in cross sectional configuration so as to be reenforced and to provide suitable attaching surfaces.

75 The invention involves an air ship so constructed that the roof portion of the deck will assist in ascent and flight, acting as a plane; the upper construction being such that it will act somewhat in the nature of a parachute and materially assist in the descent of the ship.

80 The main frame consists of a suitable metallic keel 20 bowed at the ends to provide the desired hull so constructed as to adapt it to float on water; the keel being reenforced by the truss member 21, the ends whereof are secured to the keel adjacent to the bowed 85 ends of the latter. The truss member 21 is disposed or bowed upwardly in a vertical direction to also constitute a support for the deck frame of the ship. The framework also involves the various truss members 22, the ends whereof are secured to certain of the ribs 23 of the hull and bow inwardly and upwardly into juxtaposition with the truss member 21, see Figure 13. I also provide the reenforcing longitudinal truss members 24 secured to the upwardly disposed por-

2

tions of the rib members 23 and bowed laterally toward the longitudinal center line of the ship. The truss members 24 are disposed immediately beneath the deck of the ship (see Figure 13). The various truss members, as will be seen in Figure 11, all bow toward the longitudinal center line of the ship into juxtaposition with the longitudinal deck supporting beam 25. The main framework also involves the roof supporting truss member 26, which bows downwardly toward the longitudinal center line and into juxtaposition with the previously mentioned truss members and longitudinal deck beam 25, and the truss members 27, 27, bowing inwardly and downwardly from the roof frame toward the deck beam 25, see Figure 13. These various members are preferably T-shape in cross-section, and at the intermediate point where they come into juxtaposition are all secured together and to the main or keel truss 21 by a reenforcing coupling member 28 shown in perspective in Figure 12. The member 28 consists of a metallic block of desired length provided at its longitudinal center with a T-shape slot 29 extending therethrough to receive the deck supporting beam 25. This member 28, in the specific exemplification, is shown octagonal in cross-section with each facet or face provided with a longitudinal slot 30 for the purpose of receiving the main leg of the various T-shaped truss members referred to; while the other legs or transversely disposed head portions of the truss members are intended to extend flush with the outer faces of the member 28 and to be riveted or otherwise secured thereto. The various faces or facets of the block 28 are shown provided with rivet or bolt-receiving openings 31. It will be understood that the various truss members 21, 22, 24, 26 and 27 are so arranged that the main leg of the T will enter the respective slots 30 of the reenforcing member 28. That is to say, slot 30 in the uppermost face of the member 28 is adapted to receive the roof truss member 26; the two upper sloping faces are intended to receive the truss members 27, 27; the two vertical side faces to receive the truss members 24, 24; the lowermost horizontally disposed face receives the keel truss 21; while the two lower sloping faces receive the truss members 22, 22. The framework involves suitable truss and brace members, as at 32, suitably connected to the keel and to the deck supporting beam to provide a rigid structure adapted to withstand the strains and stresses. The framework, as previously stated, is of comparatively light metal, with the keel 20 shown in the form of an I-beam having its web or intermediate portion, at spaced intervals, provided with slots adapted for the passage of the rib members 23 therethrough; the rib members like the va

rious truss members being also preferably formed of T-iron. It is apparent that with my manner of constructing the main frame, all strains are carried by the keel of the ship.

The various rib members 23 provide a suitable bottom for the air ship and are made to extend continuously about the air ship; certain of the ribs, in conjunction with the deck beam 25 and truss members 24, 24, 70 constituting the supporting frame for the deck floor; others constitute a support for the ceiling or roof of the deck and therefore constitute a support for the bottom of the compartment in which the gas holding 80 receptacles or containers of the ship are located; while other ribs are formed to extend over the gas container holding compartment; with a further set of ribs extending upwardly over the gas receptacles or containers; and still another set disposed across the outer covering of the ship, see Figures 1 and 3. This arrangement of the ribs is substantially like that disclosed and described in my pending application Serial 90 No. 52,553. That is to say, the ribs are alternately formed of different lengths so that all portions of the ship are supported from and all pulling strains or stresses are transmitted to the keel of the ship. 95

The roof of the ship involves the frame members 33, 33 extending lengthwise of the ship, with portions adjacent to the bow or forward end of the ship bowed upwardly with the intermediate part of the bowed 100 portion given a further upward curvature or bend as indicated at 34 in Figure 11; and all of the frame members 33 shown connected together at the upper bowed portions 34 by a transverse frame member 35. With this construction it will be seen that the roof adjacent to the forward end of the ship is provided with a vacuum chamber or pocket having the upper or super vacuum pocket formed by the portion 34. It will 105 be understood that my improved air ship is intended to be open from front to rear above the deck so that an air passage extending from end to end above the deck and beneath the roof is provided. This permits 110 the roof to act as a plane; while the vacuum chambers or pockets disposed above the main air passage will assist materially in lifting or elevating the ship. The roof members are intended to be provided with a suitable 115 covering, indicated at 36 in Figures 1, 3 and 8, disposed entirely across the top and downwardly along opposite sides and in spaced relation with an outer covering 37, thus providing an air chamber or space 38 120 therebetween. The outer covering 37 terminates in the laterally extended roof portion 39 as seen in Figures 1, 3 and 8. The chamber or space between the coverings 36 and 37 at the bottom is closed by the wall 39 125 130

which latter is preferably provided at various points with a number of ventilators 40, 41. The ventilators are disposed throughout the lower part of the overhanging portion of the air space or chamber and are of any suitable construction and arrangement; for example of a sliding type operatively connected together so that they may be simultaneously operated from a common point. 10 It will be understood that the overhanging outer portion of the air ship may be properly supported by any suitable number of brace rods or tie wires of the type and in the manner usually employed. The outer covering, at suitable intervals, is shown provided with vents as at 42 whereby air may be permitted to gradually escape from the upper or parachute portion of the ship.

The roof or upper portion of the ship, 20 namely the portion above the roof of the deck, is shown provided with a number of independent gas-holding chambers or tanks 43, see Figure 3, arranged in slight spaced relation to provide intervening air passages 44 which extend from the main air passage on the deck to the air chamber or space 38; the air chamber 38 it being understood extends throughout the upper portion of the ship from end to end and from side to side. 30 The gas chambers or tanks 43, as will be seen in Figure 3, are held in place against movement by certain of the upwardly disposed ribs 23; and the gas chambers or receptacles are shaped to conform to the upper portion of the ship to offer as little resistance as possible. The gas tanks or receptacles may be provided at any suitable point with filling cocks accessible from the deck of the ship and each gas tank or receptacle is provided with a conduit or pipe 45 extending downwardly to a gas-bag or preferably collapsible receptacle shown at 46 in Figures 3 and 8 arranged in a suitable protecting framework disposed along the bottom of the ship. The auxiliary gas bag or receptacle 46 is for the purpose of relieving the pressure in the gas receptacles or chambers 43; the conduits or pipes 45 being provided with suitable valves automatically operable in the event that the pressure in the gas receptacles or tanks reaches a predetermined degree, as when the ship has attained a certain altitude. By providing the auxiliary gas-receiving bag, 50 the pressure in the gas tanks may thus automatically be relieved and loss of the gas thus prevented.

In the construction as illustrated in Figures 1, 3 and 9, the ship is provided at the bow or forward end and at the longitudinal center line with a pilot cabin indicated at 47 and with the cabins 48, 48 at opposite sides of the ship adjacent to the stern thereof, thus providing an open air passage on opposite sides of the pilot cabin having an

intermediate restricted portion at a point intermediate of the cabins 48 and flaring toward the stern of the ship.

In Figure 14 I show a modification of the deck portion of the ship in so far as the arrangement of the cabins are concerned; the forward portion of the ship being provided with the pilot cabin 47 as in Figure 9, while the cabin or stateroom compartment is located at the longitudinal center line of the ship as indicated at 49 in Figure 14, thus causing the air passage above the deck to be divided by the compartment 49; the walls of the cabins and compartments being formed to offer as little resistance as possible. 70 75 80

The deck is shown provided with a number of hatchways generally indicated at 50, while the cabins are shown provided with stairs at 51 to permit access to the engine or motor compartment in the hull of the ship and to the cargo containing portion of the hull which latter is shown in Figure 10. 85

The ship in the specific exemplification is shown provided with a number of high speed motors generally indicated at 52 suitably mounted in the bow and stern of the hull for the purpose of operating the respective propellers 53 and to provide power for operating any of the other power actuated elements of the ship. The hull of the ship is provided with a plurality of partitions 54 for dividing the hull into a series of suitable compartments for the purpose of holding the lading and maintaining the latter in its distributed position to properly equalize or distribute the weight throughout the ship and to prevent such shifting of the lading as would disturb the equilibrium of the ship. The partitions in the hull are arranged to provide the gangways or passages 55, 56, see Figure 10 and the various partitions may be provided with slide doors or other suitable closure members 57 to permit access to the respective compartments. 90 95 100 105 110 115

The ship, intermediate of the deck and the roof portion 36, namely at the point where the roof is given the upward bulge or arcuate formation to provide the vacuum chamber and super-vacuum pocket, is shown provided with a suitable number of planes indicated at 58 and 59 arranged one above the other in spaced relation and extending preferably entirely across the deck intermediate of the side walls, with the exception of the lower plane 59, the end portions or sections 59^a, 59^b whereof extend through suitable openings formed in the side walls of the ship. The planes 58, 58 are preferably rigidly secured in place with the rearward 120 125 130

and downward slope or declination, see Figure 3, in order that the air rushing through the passageway on the deck when encountering the planes 58, 58 will assist in lifting the ship. The planes are supported and braced in any suitable manner, as for example by means of rods 60, 60 secured to the ship frame and preferably suitably connected to certain of the main frame members 10 in order that the lifting strains may be transferred to the keel or main frame portions of the ship. The lower plane as previously stated consists of the intermediate section 59 disposed transversely of the longitudinal center line of the ship and the two end sections 59^a which extend out beyond the sides of the ship. These sections are hingedly secured in place in any suitable manner, as for example by having the 15 forward portions of the sections hingedly secured at 61 and each section adapted to be independently controlled in any suitable manner, as for example by means of wires or cables 62 which may extend downwardly 20 through the deck about pulleys and adapted to be controlled from a common point by the pilot. As previously stated, the various sections of the lower plane may be simultaneously tilted to a proper angle relative to the line of flight or the sections may be separately operated and set at varying 25 inclinations or angles.

The ship is also shown provided with the side wings or planes 63, 63 arranged on opposite sides and of any suitable construction and size; the wings or planes 63 being either fixedly secured in place or hingedly mounted as defined in my previous application Serial No. 52,553.

The sides of the ship adjacent to the bow and adjacent to the stern is also shown provided with the auxiliary wings or planes 64, 64 and 65, 65, see Figures 9 and 14. The stern of the ship is shown provided 45 with a rudder indicated at 66. The planes 65 may be arranged in pairs one above the other as shown in Figure 1, supported by any suitable frame and the planes all controlled and operable from a common point, namely the pilot cabin by any suitable mechanism which need not be described.

The construction illustrated in Figure 7 is substantially the construction of the air ship previously described, except that the gas receptacle holding portion of the ship above the roof is omitted. The construction in Figure 7 discloses a heavier than air ship, in which the roof, as previously stated, acts as a plane and is provided with the vacuum chamber and super-vacuum pocket which will materially assist in lifting the ship.

The bottom of the ship is shown provided with beams or runners 67, 67 extending lengthwise on opposite sides of the keel. 60 These runners at the same time act as stiff-

eners for the frame. 68 is an observation tower.

I have shown what I believe to be simple embodiments of my invention which have been described in terms employed merely as 70 terms of description and not as terms of limitation as structural modifications are possible and may be made without departing from the spirit of my invention.

What I claim is:

1. In an air ship provided with a deck, side walls extending above the deck and a ceiling or roof, the ship at the bow and stern and between the deck and roof being open to provide an air passage lengthwise of the ship, a plurality of planes arranged transversely of the ship one above the other between the deck and the roof, one of said planes being formed in sections, with the end section disposed beyond the side walls, 80 and means for tilting said plane-sections.

2. In an air ship provided with a deck, side walls extending above the deck and a roof, the walls at the bow and the stern being open to provide an air passage lengthwise of the ship between the deck and roof, a sectional plane arranged transversely of the ship between the deck and roof, with the end sections extending beyond the side walls, 85 said sections being pivotally mounted, and means whereby said sections may be separately tilted.

3. In an air ship, a frame comprising a keel, transversely disposed ribs, a deck beam, 100 roof members, truss members secured, respectively, to the keel, to the ribs and to the roof members, all of said truss members being bowed toward a common point on said deck beam, and a coupling member common to all of the said truss members whereby the latter are reinforced and coupled to the deck beam.

4. In an air ship, a frame comprising a keel, ribs disposed transversely of the keel and disposed upwardly at opposite sides of the ship, roof members, a deck beam, truss members secured at their ends, respectively, to the keel, to ribs and to the roof members, all bowing toward the deck beam, and a slotted coupling member adapted to receive an intermediate portion of all of the truss members and of the deck beam whereby the truss members and deck beam are coupled together.

5. In an air ship, a frame comprising a keel, ribs disposed transversely through the keel and disposed upwardly at opposite sides of the ship, roof members disposed lengthwise of the ship, a deck beam, truss members secured at their ends, respectively, to the keel, to the ribs and to the roof members and extending lengthwise of the ship, 115 all of said truss members bowing inwardly toward the deck beam, a coupling member slotted through the center to receive the 120

deck beam and slotted on its outer perimeter to receive the respective truss members, and means for securing the coupling member to the truss members.

- 5 6. In an air ship, a frame comprising a deck beam extending lengthwise of the ship, truss members disposed above, beneath and on opposite sides of the beam, all of said truss members bowing toward the deck beam, and a coupling member composed of a metallic block cored at its center for passage of the deck beam therethrough, the sides of the block being longitudinally slotted to receive the respective truss members
- 10 15 which are riveted thereto.

7. In an air ship, a frame comprising a keel, the ends whereof are bowed upwardly, a deck beam secured at its ends to the keel ends, ribs disposed transversely of the keel and secured thereto, all of said ribs being disposed upwardly at opposite sides of the ship, roof members secured to the upwardly disposed ends of the keel, truss members secured, respectively, to the keel, the ribs and to the roof members and all bowing inwardly toward a common point on the deck beam, and a coupling member composed of an elongated block provided with a plurality of outer faces corresponding in number with the number of truss members, the center of the block being cored to correspond with the cross-sectional configuration of the deck beam to permit its passage therethrough while each of its faces is slotted to receive the respective truss members.

8. In an air ship, a frame comprising a keel consisting of an I-beam having upwardly disposed ends and provided with openings through the web portion, ribs of T-iron disposed through said openings in the web of the keel, a T-shaped deck beam, T-shaped roof members, T-shaped truss members, all of the truss members bowing inwardly toward the deck beam, and coupling means consisting of an elongated block having a T-shaped opening therethrough at its longitudinal center to receive the deck-beam, the block being of polygonal cross-section with each face slotted longitudinally to receive the main leg of the T-iron constituting the various truss members, while the laterally disposed head portions of the T-irons are secured on the respective faces of the elongated block.

- 55 9. In an air ship, a frame comprising a deck beam, truss members disposed lengthwise of the ship and all bowed inwardly toward the deck beam, the beam and truss members being T-shaped in cross-section, and a coupling member comprising an elongated metallic block of polygonal cross-section, a T-shaped slot through the block adapted to receive the deck beam while each outer face is slotted longitudinally to receive a leg of a truss member, with the trans-

verse head portion of each truss member disposed flush with a flat face of the coupling member and secured thereto.

10. An air ship comprising a hull portion provided with a deck, the hull portion beneath the deck being divided into lading receiving compartments uniformly arranged on opposite sides of the median line of the ship and motor containing compartments, all of said compartments being independently accessible, a pilot cabin on the deck at the bow and median line of the ship, passenger cabins on the deck toward the stern of the ship, and a roof over the deck provided with an upward bulge disposed transversely between the front and rear ends of the ship, and side walls open at the front and rear ends of the ship whereby an air passage lengthwise of the deck is provided.

11. An air ship comprising a hull portion provided with a deck, a roof portion above the deck, cabins on the deck arranged so as to provide an open air passage between the deck and roof portion and extending from end to end of the air ship, gas-holding chambers arranged in the roof portion, an auxiliary gas-holding receptacle in the hull portion, and connections intermediate of the gas-holding chambers and the auxiliary gas-holding receptacle adapted to convey the gas from the gas-holding chambers to said auxiliary receptacle.

12. An air ship comprising a hull portion provided with a deck, a roof portion provided with gas-holding chambers, side walls disposed upwardly from the hull portion to the roof portion open at the front and rear ends of the ship to provide an air passage lengthwise of the deck, an auxiliary gas-receiving receptacle located in the hull portion and having valved conduit connection with the gas-holding chambers for receiving the gas from said chambers when the pressure exceeds a predetermined degree.

13. An air ship comprising a hull portion provided with a deck, a roof portion above the deck adapted to act as a carrier or plane, side walls disposed from the hull portion over the roof portion with openings at the front and rear ends of the ship to provide an air passage between the deck and roof, a rudder arranged in alignment with the rear end of said air passage, vertically spaced planes arranged intermediate of the deck and roof, one of said planes being made in sections with the end sections extending beyond the sides of the ship, the sections being tiltably mounted, vertically spaced planes arranged in pairs on each side of the rudder, a wing secured to each side of the ship, propellers fore and aft, and means whereby the sections of the sectional plane may be independently operated.

14. A power driven air ship comprising a hull provided with a deck, a roof substanti-

ally coextensive with and disposed throughout the length of the deck and provided with an upward bulge or pocket disposed transversely from side to side of the roof intermediate of the fore and aft part thereof, cabins arranged on the deck, the walls of the cabins reaching from deck to roof and formed to provide an air passage between the deck and roof, and a rudder arranged at the stern in alignment with said air passage.

15. An air ship provided with a roof and comprising a keel, a deck beam disposed lengthwise above the keel, truss beams intermediate of the keel and the deck beam and intermediate of the deck beam and the roof, and a coupling member common to all of the truss members and the deck beam.

16. An air ship comprising a keel, a deck beam, transverse ribs all secured to the keel with certain of the ribs constituting deck supports, a second portion constituting roof supports, a third portion constituting outer covering supports, truss members intermediate of the keel and deck beam and intermediate of the deck beam and roof, all of the truss members bowing toward the deck beam, and a coupling member common to all of the truss members whereby they are coupled to the deck beam.

17. In an air ship provided with a deck,

side walls extending above the deck, a roof, an open ended air passage between the deck and roof extending from bow to stern, and a sectional plane arranged between deck and roof transversely of the ship with the sections pivotally mounted and separately tiltable.

18. An air ship provided with a keel, a deck beam, roof members, truss members between the keel and deck beam and between the deck beam and roof members, all of the truss members bowing toward a common point, and a coupling member adapted to receive the deck beam and all of said truss members whereby all strains are transmitted to the keel, the portion of the ship beneath the deck being provided with a plurality of compartments arranged uniformly on opposite sides of the median line of the ship, with all of the compartments independently accessible from the deck of the ship.

19. An air ship comprising a hull portion provided with a deck, the hull portion beneath the deck being divided into lading receiving compartments uniformly arranged on opposite sides of the median line of the ship and motor containing compartments, all of said compartments being independently accessible.

LAWRENCE W. MAMMEN.
